UNITED STATES PATENT OFFICE.

JOSEPH E. STRAKER, JR., OF ATTLEBORO, MASSACHUSETTS, ASSIGNOR TO
WATSON & NEWELL COMPANY, A CORPORATION OF RHODE ISLAND.

DESIGN FOR A HANDLE FOR SPOONS, FORKS, OR SIMILAR ARTICLES.

SPECIFICATION forming part of Design No. 37,070, dated August 9, 1904.

Application filed February 13, 1904. Serial No. 193,479. Term of patent 7 years.

To all whom it may concern:

Be it known that I, JOSEPH E. STRAKER, Jr., a citizen of the United States, residing at Attleboro, in the county of Bristol and Commonwealth of Massachusetts, have invented a new, original, and ornamental Design for the Handle of a Spoon, Fork, or Similar Article, which is illustrated in the accompanying drawings, forming part of this specification.

10 In the drawings, Figure 1 shows the face

view of a spoon or fork upon the handle of which is my new design, and Fig. 2 is an edge view of the same.

My claim is—

The ornamental design for the handle of a 15 spoon, fork or similar article as shown.

JOSEPH E. STRAKER, JR.
